Sherman, Jewitt & Francis H. Root, of Buffalo, N.Y.
Letters Patent No. 1099. Dated May, 3d, 1859.

The schedule referred to in these Letters Patent and making part of the same.

To all whom it may concern:

Be it known that we Sherman S. Jewitt and Francis H. Root, of the City of Buffalo, County of Erie, State of New York, have invented a new and original design for the ornamentation of Cooking Stoves, which we designate by the name of the Fortune, of which the following in connection with the accompanying drawings is a full clear and exact description.

Fig. 1st. in these drawings represents the front plate of the stove surrounded by sliding doors and the embellishment of the parts consists of a panel on either jam with a recessed center (a) in relief, surrounded by a bead scalloped moulding (b) and between the side panels over the fire opening is a horizontal band (c) of ovate shaped bosses.

The sliding doors are panelled by mouldings in relief with a scalloped sea shell (e) in the center, also in relief, and between the panels and inner edge of the door, is a vertical bossed band (f) the same as that over the fire opening.

The side plate to the stove represented in Fig. 2^d. is ornamented by a series of ovate bosses (g) and surrounded by a light moulding.

The side door in this plate, like the sliding doors, is panelled with a scalloped sea shell (h) in the center of the panel, differing slightly from those in the sliding doors.

In Fig. 4 is represented the side plate to the oven. This plate is surrounded by a broad moulding, ornamented with alternate leaves and striae and the inner edge of the moulding is denticated.

A central panel rounded at the corners and finished with a moulding (K) has a center piece consisting of a plain ovate shield (i) beaded at the outer edge, and surrounded by a wreath (m) of flowers and leaves in clusters at the ends of the shield, and sea shells at the top and bottom all in relief.

The design on the oven door and frame represented in Fig. 3, consists of a plain ovate shield (m) in the center of the door panel, the same as that on the side plate and surrounded by a wreath (o) of flowers stalks and leaves. An ornamental moulding (p) of alternate leaves and striae also surrounds the edge of the door, and the edge of the door frame has a moulding around it, the inner edge of which is ornamented slightly by alternate ridges and concave depressions rounded at the point.

The top plate of the oven, represented in Fig. 5, is toothed around the edge of the openings for the utensils, and the angle of the first offset is filled by a beaded fillet (s) and below this point in the concave part of the top is a band of scallops - scalloped or tongued ornaments with a central drop.

Having thus described our ornamental design for a stove,

What we claim as new and desire to secure by letters patent is the ornamental configuration and design for the plates of a stove as described & shown in the accompanying drawings.

Testimony whereof we have subscribed our names.

Witnesses.
